HANDLE FOR IMPLEMENTS, UTENSILS, AND
THE LIKE AND METHOD OF MAKING THE
SAMEWilliam H. Gollan, Decatur, Ill., assignor to U. S.
Manufacturing Corporation, Decatur, Ill., a
corporation of Illinois

Application March 14, 1936, Serial No. 68,795

23 Claims. (Cl. 140—71)

This invention relates to improvements in handles for implements, utensils and the like, and the principal object is the provision of a handle member which is composed entirely of one piece of wire or rod which is operated upon to provide a complete handle, including a securing loop adapted to be connected to the implement or utensil and also if desired, provided with a gripping loop for manually operating or holding the implement or utensil.

The handle construction is simple and strong, it is attractive in appearance and lends itself readily to factory production on a commercial basis at a cheap cost.

To the accomplishment of the foregoing and such other objects as may hereinafter appear, this invention consists in the construction, combination and arrangement of parts hereinafter described and then sought to be defined in the appended claims, reference being had to the accompanying drawings forming a part hereof and which show, merely for the purpose of illustrative disclosure, several embodiments of my invention, it being expressly understood, however, that various changes may be made in practice within the scope of the claims without digressing from my inventive idea.

In the drawings

Fig. 1 represents a side elevation of a suitable length of wire or rod which is the raw material from which the final handle member is made.

Fig. 2 is a side elevation illustrating the first step in the operation of forming the handle member.

Fig. 3 is a side elevation indicating the next step in the operation of forming the handle member.

Figs. 4 and 5 are cross sections taken substantially on lines 4—4 and 5—5 of Fig. 3;

Fig. 6 is a detailed elevational view showing the method whereby the securing loop element is formed from the blank shown in Fig. 3;

Fig. 7 is a fly swatter provided with a handle constructed in accordance with the disclosures of preceding figures of the drawings;

Fig. 8 is a side elevation of a suitable length of raw material after it has been subjected to the first operation in forming a modified construction;

Fig. 9 is a similar view showing the blank after the next step in the method has taken place;

Fig. 10 is a similar view showing the blank after the next step has taken place as a result of which the triangular securing loop is formed at

the upper end and the open gripping loop is formed at the lower end.

Fig. 11 is a side elevation of a fly swatter provided with a handle construction substantially as shown in Fig. 10;

Figs. 12 and 13 are detailed views showing constructions of the lower end of the handle member which differ from that shown in Figs. 2 and 3. These views illustrate a slightly different form of anchoring means for securing the gripping element to the handle member.

Fig. 1 shows a suitable length of rod or wire 1 which I will call a blank. In the method of making the handle member this blank has its upper portion flattened as at 2, Fig. 2, and has portions 15 squeezed or struck out from its lower part near its lower end as indicated at 3, Fig. 2. In the next operation the flattened part 2 is cut or split as at 4 to provide two separate portions or arms. These arms are then bent in the form of an open 20 triangular loop 5, see Fig. 7. This triangular loop is formed by bending the flattened arms which are provided when the flattened part 2 is cut or split as at 4, and includes the diverging legs 6 and 7 which are bent as at 8 to form the inwardly extending horizontal portions 9, the free ends of which are located in juxtaposition. These parts form the upper horizontal leg of the triangular loop 5.

The fly swatter shown in Fig. 7 has a body 10 30 of conventional shape or construction, it being substantially rectangular, with the lower corner portions 11 folded along lines 12 converging to a point to form a triangular pocket. The open triangular securing loop 5 is positioned within 35 this pocket with the diverging sides or legs 6 and 7 positioned within the folds in the lower part of the body. It is held in position by any suitable means, such as staples, stitching and the like, and being flat will be securely held in position and 40 will not cause undue thickening or bulging of the lower part of the body of the fly swatter.

In the construction shown in Fig. 7, a gripping element 13 is provided, made of a suitable material and shape into which the lower end of the handle element 1 is inserted and held against 45 rotation and withdrawal because of the engagement of the struck-up lugs 3 with the material of which the gripping element is made.

As shown in Figs. 12 and 13 the form of these struck-up elements may be varied. As shown in Fig. 12 these members 14 are located together and are formed to provide teeth or serrated members which permit the insertion of the lower end 50 of the handle member within the gripping ele- 55

ment 13 but prevent its withdrawal as well as relative rotation. In Fig. 13 these teeth 14' are separated from each other longitudinally of the handle element.

5. The construction of the device shown in Figs. 8 to 11 inclusive, is somewhat different from that shown in the previous figures of the drawings. Here the blank 1 has both its upper portion 15 and its lower portion 16 flattened. As shown in Fig. 9 these flattened portions 15 and 16 are slit or cut as at 17 and 18, but which slits or cuts terminate short of the extreme ends of the blank and really formed closed slits or cuts. The next step is the formation of the upper flattened portion 15 into the closed triangular loop 19, see Fig. 10, and also the formation of the lower flattened portion 16 into the closed elongated loop 20 which forms the gripping element. The connection of this handle construction to the fly swatter body is substantially the same as that previously described and the relative advantages are also substantially the same. Furthermore, the gripping element is formed as an integral part of the handle member instead of being formed as a separate element as in the construction shown in Fig. 7.

While this handle construction is illustrated as being used in connection with a fly swatter, it is to be understood that it may be also used in connection with other utensils and implements. The triangular securing loop affords a ready means of connecting the handle member to the desired utensil or implement. The handle construction affords sufficient strength and rigidity, depending upon the kind of material used, and of course if desired, may have any desired resiliency. The construction being integral is very strong and is simple and attractive in appearance. By having the securing loop formed of flattened material, the connection between the securing loop and the implement or utensil may be made as illustrated in Figs. 7 and 11 without bulging or undue thickness, and furthermore, where other forms of implements or utensils are used, the connection with them may be readily made by brazing, soldering and the like, the flattened triangular securing loop facilitating this operation and insuring an accurate and a strong connection between the parts.

50. What I claim is:

1. A handle for implements, utensils and the like, comprising a one-piece element formed from a suitable length of wire or rod having one end flattened and slit, which slit portions are then bent relative to one another into the form of an open triangular securing loop.
2. A handle for implements, utensils and the like, comprising a one-piece element formed from a suitable length of wire or rod having one end flattened and slit and then bent into the form of an open triangular securing loop, said triangular securing loop having the surfaces of all of its legs flattened.
3. A handle for implements, utensils and the like, comprising a one-piece element formed from a suitable length of wire or rod having one end flattened and slit and then bent into the form of an open triangular securing loop and having its other end flattened and slit and bent to form an open gripping loop.
4. The method of making handles for implements, utensils and the like, which includes flattening one end of a suitable length of rod or wire, slitting said flattened portion, bending the slit

parts of said flattened portion into the form of an open triangular loop whereby a triangular securing loop with flat surfaces is provided.

5. The method of making handles for utensils, implements and the like which includes flattening both end portions of a suitable length of rod or wire, slitting said flattened portions and bending one of said slitted flattened portions into an open triangular securing loop and bending the other slitted flattened portion to form a gripping element.

6. A handle for implements, utensils and the like, comprising a one-piece element formed of a suitable length of wire or rod having one end flattened and slit to form two arms, said two arms then being bent into the form of an open securing loop, the extreme ends of said arms being bent along straight lines into alignment with each other so that the upper edge of the securing loop is substantially horizontal and straight.

7. A handle for implements, utensils and the like, comprising a one-piece element formed of a suitable length of wire or rod having one end flattened and slit to form two arms, said two arms then being bent into the form of an open substantially triangular shaped securing loop, the extreme ends of said arms being bent along straight lines into alignment with each other so that the upper edge of the securing loop is substantially horizontal and straight.

8. A handle for implements, utensils and the like, comprising a suitable length of wire or rod having one end portion thereof slit, the slit portions being bent relative to one another to form an open substantially triangular shaped securing loop, and also having a portion of its other end slit with the slit portions thereof bent relative to one another to form an elongated gripping element.

9. A handle for implements, utensils and the like, comprising a one-piece element formed from a suitable length of a single piece of straight wire or rod, one extreme end portion of which straight wire or rod is flattened and bent to form an open substantially triangular shaped loop.

10. A handle for implements, utensils and the like, comprising a suitable length of wire or rod having two flattened arms integral therewith at one end portion thereof, and the two arms bent relative to one another to form a substantially triangular shaped open loop.

11. A handle for implements, utensils and the like, comprising a suitable length of wire or rod having two flattened arms integral therewith at one end portion thereof, one end of each of which arms is free and unconnected, and the two said arms bent relative to one another to form an open loop with the unconnected end portions of the arms extending toward one another.

12. A handle for implements, utensils and the like, comprising a suitable length of wire or rod having an end portion thereof slit, and the slit portions bent relative to one another to form a substantially triangular shaped open loop.

13. A handle for implements, utensils and the like, comprising a suitable length of wire or rod having one end portion thereof slit to form two arms, and said two arms bent relative to one another to form a substantially triangular shaped open loop.

14. A handle for implements, utensils and the like, comprising a suitable length of wire or rod having one end portion thereof slit to form two independent arms one end of each of which arms is free and unconnected, and the said two

arms bent relative to one another to form an open loop with the unconnected end portions of the arms extending toward one another.

5 15. A handle for implements, utensils and the like, comprising a suitable length of wire or rod having one end portion thereof flattened and slit, and the flattened slit portions bent relative to one another to form a substantially triangular shaped open loop.

10 16. A handle for implements, utensils and the like, comprising a suitable length of wire or rod having one end portion flattened and slit to form two arms, and the flattened and slit arms bent relative to one another to form a substantially triangular shaped open loop.

15 17. A handle for implements, utensils and the like, comprising a suitable length of wire or rod having one end portion thereof flattened and slit to form two independent arms, one end of each of 20 which arms is free and unconnected, the said two arms bent relative to one another to form an open loop with the unconnected end portions of the arms extending toward one another.

20 18. The method of making handles for implements, utensils and the like, which includes flattening one extreme end portion of a suitable length of rod or wire and bending the flattened portion to form a substantially triangular shaped open loop.

25 19. The method of making handles for implements, utensils and the like, which includes flattening one end portion of a suitable length of wire or rod, slitting said flattened portion, and bend-

ing the slit portions relative to one another to form a substantially triangular shaped open loop.

20 20. The method of making handles for implements, utensils and the like which includes slitting one end portion of a suitable length of stock, and bending the slit portions relative to one another to form a substantially triangular shaped open loop.

10 21. The method of making handles for implements, utensils and the like which includes flattening both end portions of a suitable length of rod or wire, bending one of said flattened portions into an open securing loop of substantially triangular shape and bending the other flattened 15 portion to form an elongated gripping element.

20 22. The method of making handles for implements, utensils and the like which includes flattening both end portions of a suitable length of rod or wire, slitting said flattened portions, bending one of said slitted flattened portions to form a substantially triangular shaped securing loop and bending the other slitted flattened portion to form an elongated gripping element.

25 23. The method of making handles for implements, utensils and the like which includes slitting both end portions of a suitable length of stock, bending one of said slitted portions to form a substantially triangular shaped open loop and bending the other slitted portion to form a grip- 30
